LUMINOUS SYMBOL FOR ADVERTISING PURPOSES

Kurt Wiegand, Berlin-Hohen-Neuendorf, Germany, assignor to General Electric Company, a corporation of New York

Application December 15, 1938, Serial No. 245,864
In Germany February 22, 1938

3 Claims. (Cl. 40—130)

My invention pertains generally to luminous symbols for advertising purposes and also for signal purposes, and more particularly to symbols wherein electric luminous tubes are arranged to stand free and form the symbol in double lines.

An object of my invention is to provide means for rigidly and dependably supporting the luminous tube or tubes and giving to the symbol a novel and pleasing day and night effect. For this purpose, an intermediate core or strip member bent in the same shape as the symbol or letter and arranged on edge is disposed between the parallel luminous tube parts and is fastened to a base housing and serves as a support for the luminous tube. The core or strip member which may be made of flat iron, is preferably made wider than the luminous tube diameter in order to reduce the possibility of damaging the luminous symbol, and is so arranged that it projects uniformly on both sides of the luminous tube. Since the luminous tube can easily be fastened securely to the core member, it is not necessary to further specially secure the sensitive terminals or electrode vessels in the base housing. By fastening the luminous tube to the special core member, the electrode vessels are relieved of the weight of the luminous tube.

The drawing shows a letter-shaped luminous symbol comprising my invention wherein Fig. 1 is a front view of the luminous letter; Fig. 2 is a side view thereof; Fig. 3 is a section on the line A—B of Fig. 1; and Fig. 4 is an enlarged plan view showing the left hand end of the base housing.

The electric luminous tube 1, which forms the outline of the luminous letter, in the present case an R, with its electrodes 2, 3 and with its return bend 4 which forms the end of the letter, extends into the base housing 5. For this purpose, the latter, in its cover plate 6, has two rectangular openings 7 which, at the places of entrance of the luminous tube also have small semi-circular recesses 8. These openings 7, after the insertion of the electrodes and of the return-end 4 of the luminous tube into the housing, are covered by rectangular plates 9 which, by means of screws 10, are fastened to the cover plate 6 of the housing, and by means of screws 11 to the front plate 12 of the housing. These cover plates 9 likewise have semi-circular recesses 8' which, together with the recesses 8 of the housing cover plate 6, form a circular opening surrounding the portions of the luminous tubes emerging from the housing. The front plate 12 of the housing 5 is preferably removably set in, as shown in Fig. 2. In the back

wall 13 of the housing 5 there is an opening 15 which is strengthened by a ring 14 and is provided for the passage of the conductor cables which are to be attached to the luminous tube electrodes or terminals.

The luminous tube 1, which forms the outline of the letter surrounds a core-letter or strip member 16 which lies in the same plane and which may consist of a flat iron strip placed on edge so that it is readable edgewise. This flat iron strip, as shown in Fig. 2, is wider than the diameter of the luminous tube, by virtue of which it projects uniformly beyond the tube on both sides. The base-ends of the core-letter 16 have secured thereto, preferably by welding, angle sheets 17, 18 which are fastened to the cover plate 6 of the housing 5 by means of screws 19. For the purpose of stiffening the core-letter, it is provided at its midpart with a connecting strip 20 welded thereto.

The core-letter 16, which serves as a support for luminous tube 1, is equipped with a number of fastening members for the latter. These fastening members may each consist of an upright bolt 23 which is fastened to the core-letter by means of a nut 21 and locknut 22, and whose end facing the luminous tube carries a semi-circular bow 24 with somewhat bent-over ends, into which wire loops 25 are laid, which wire loops surround the luminous tube. The number of fastening bolts 23 depends on the size of the luminous letter, which in this manner can be braced and held, to a certain extent over its entire length.

The core-letter 16 may be colored so as to present a contrasting appearance to the colored luminous tube, so that the luminous letter also offers a good daylight effect. The said core-letter may also be provided with mirror or reflecting coatings. At night a sharp separation of the light-lines created by the tubes is produced by the core body located between the parallel luminous tube parts, which fact considerably improves the appearance of the luminous symbol.

The letter symbol, instead of consisting of a single luminous tube, may also consist of two parallel extending luminous tubes, in which case four electrodes must then be enclosed in the base housing. In place of an electric discharge luminous tube, an incandescent luminous tube or tubes with a metallic filament extending longitudinally of the tube, can also be provided.

What I claim as new and desire to secure by Letters Patent of the United States is:

1. A luminous symbol comprising a strip-like core member bent to the shape of the desired

- symbol so as to be readable edgewise, and electric luminous tube means extending parallel to and on both sides of said core member to form the luminous symbol in double lines, said luminous tube means being supported directly from said core member.
2. A luminous symbol comprising a base housing, an upright strip-like core member bent to the shape of the desired symbol so as to be readable edgewise, said core member being mounted on said housing, and electric luminous tube means extending parallel to and on both sides of said core member to form the luminous symbol in double lines, the terminals of said tube
- 5 means extending into said housing, said luminous tube means being supported directly from said core member independently of said housing.
- 10 3. A luminous symbol comprising a strip-like core member bent to the shape of the desired symbol so as to be readable edgewise, and electric luminous tube means extending parallel to and on both sides of said core member to form the luminous symbol in double lines, said core member being wider than the diameter of said tube means and projecting beyond both sides thereof, said luminous tube means being supported directly from said core member.

KURT WIEGAND.
